UNITED STATES PATENT OFFICE.

EDWARD A. CHRISTOPH, OF CHICAGO, ILLINOIS, ASSIGNOR OF ONE-HALF TO JACOB W. ELVYN, OF CHICAGO, ILLINOIS.

ADVERTISING DEVICE.

1,197,791.

Specification of Letters Patent. Patented Sept. 12, 1916.

Application filed July 24, 1915. Serial No. 41,733.

To all whom it may concern:

Be it known that I, EDWARD A. CHRISTOPH, a citizen of the United States, residing at Chicago, in the county of Cook and State of Illinois, have invented a certain new and useful Improvement in Advertising Devices, of which the following is a full, clear, concise, and exact description, reference being had to the accompanying drawings, forming 10 a part of this specification.

My invention relates to advertising devices and contemplates a structure which can be manually manipulated so as to present two conditions and appearances. In 15 one condition advertising matter of one sort may be exposed, and in another condition, other advertising matter may be exposed.

Furthermore, it is the object of my invention to provide a structure of this kind in 20 the nature of a mailing card and I therefore provide a structure which may conveniently be made of paste-board and which is of such arrangement that advertising matter upon the interior may be normally withheld from 25 view.

In accordance with the spirit of my invention, I provide a shutter arrangement which makes possible the two conditions heretofore described and which at the same 30 time acts as a lock to hold the mailing card in closed condition.

My invention is illustrated in the accompanying drawings, in which—

Figure 1 is a face view of the device of 35 my invention in one condition. Fig. 2 is a face view thereof in its other condition. Fig. 3 is an enlarged sectional view taken on the plane of the line 3, 3 of Fig. 1 and looking in the direction indicated by the arrows.

It will be seen that I provide a back wall 40 4 which is provided upon the top with a flap 5 and upon the bottom with a flap 6. These two flaps when folded down one upon the other, as illustrated in the drawings, close 45 the mailing card and normally hides from view any advertising matter that may be contained on the face of the card. The flap 5 is provided with an opening 7 which I shall refer to again and with a downwardly 50 extending tongue 8. This tongue 8 passes inwardly through a slit 9 in the flap 6 and also through a slit 10 coincident with the crease between the back wall 4 and the flap 6. The flap 6 is provided with an opening 11

which I shall refer to again presently, and is 55 also provided with an upward tongue 12 which is adapted to pass through a slit 13 coincident with the crease between the flap 5 and the back wall 4. It will thus be seen that when the structure is in the normal condition illustrated in Fig. 1, the tongue 8 extends downwardly through the slit 9 and to the slit 10, while the tongue 12 extends upwardly to the slit 13. In this condition certain printing matter on the flap 6 is exposed 60 through the opening 7, as illustrated in Fig. 1, nothing being exposed through the opening 11, if so desired. When the structure is grasped at the top and bottom and squeezed together so as to buckle the back wall, as 70 illustrated in Fig. 2, the tongue 8 will pass downwardly out of the slit 10, the tongue 12 will pass upwardly out of the slit 13, and certain printing matter, other than that exposed in the condition of Fig. 1 will be exposed 75 through the opening 7 and certain printing matter upon the tongue 8 will be exposed through the opening 11, all as illustrated in Fig. 2. The tongues themselves may have printing matter thereon. 80

It will be seen that passing the tongue downwardly through the slit 9 locks the folder in closed position, as illustrated in Fig. 3.

The face of the folder may be provided 85 for lines for an address and has room for a postage stamp.

I claim as new and desire to secure by Letters Patent:

1. In an advertising device, a back wall, a 90 flap extending from the top thereof, a flap extending from the bottom thereof, each flap having a tongue thereon, said flaps folded one over the other, and said tongues when said back is buckled extending through 95 slits and exposing their ends.

2. In an advertising device, a back wall, a flap extending from the top thereof, a flap extending from the bottom thereof, each flap having a tongue thereon, said flaps folded 100 one over the other, and said tongues when said back is buckled extending through slits, coincident with the creases between the back wall and said flaps.

3. In an advertising device, a back wall, a 105 flap extending from the top thereof, a flap extending from the bottom thereof, each flap having a tongue thereon, said flaps folded

one over the other, and said tongues when said back is buckled extending through slits and beyond the periphery of the back wall.

4. In an advertising device, a back wall, a flap extending from the top thereof, a flap extending from the bottom thereof, each flap having a tongue thereon, said flaps folded one over the other, and said tongues when said back is buckled extending through slits and exposing their ends, said flaps having openings through which printing may be exposed.

5. In combination, a back wall, a flap extending from the top thereof, a flap extend-

ing from the bottom thereof, each flap having a tongue, and said flaps folded one over the other, the under tongue being adapted to extend through a slit coincident with the crease between the back wall and the upper flap, and the tongue on the upper flap extending through a slit in the lower flap and adapted to extend through a slit coincident with the crease between the back wall and lower flap.

In witness whereof, I hereunto subscribe my name this 22nd day of July A. D. 1915.

EDWARD A. CHRISTOPH.

Copies of this patent may be obtained for five cents each, by addressing the "Commissioner of Patents, Washington, D. C."
